UNITED STATES PATENT OFFICE.

JOHN G. SEEBOLD, OF MONTREAL, QUEBEC, CANADA.

PIANO SOUNDING-BOARD ATTACHMENT.

SPECIFICATION forming part of Letters Patent No. 252,146, dated January 10, 1882.

Application filed April 26, 1881. (Model.)

To all whom it may concern:

Be it known that I, JOHN G. SEEBOLD, of Montreal, Province of Quebec, Dominion of Canada, have invented a new and useful Improvement in Sounding-Board Attachments, of which the following is a specification.

The object of my invention is to provide a certain new and useful improvement in sounding-board attachments, whereby the quantity and quality of the tones will be augmented and equalized.

The invention consists in the combination, with a sounding-board, of an upright strip furnished with an aperture for each string between the bridge and the hitch-pin block, the strings resting against the upper edge of the apertures.

In the accompanying drawings, Figure 1 is a plan view of a sounding-board provided with my improvement. Fig. 2 is a longitudinal elevation of the same on the line x x , Fig. 1; and Fig. 3 is a longitudinal elevation of the apertured metal plate constituting my improvement in sounding boards.

Similar letters of reference indicate corresponding parts.

An upright strip of metal provided with an aperture, B, for each string is attached to the sounding-board C between the bridge D and the hitch-pin block E, the strings M passing from the tuning-pins F F in the tuning pin block G, over the bridge D, through the aperture B of the plate or strip A, to the hitch-pins H on the hitch-pin block E. The upper edge of the apertures B is slightly lower than the bearing-surfaces of the bridge D and the hitch-

pin block E, so that the strings will be inclined from the bearing-surfaces of the bridge and the hitch-pin block to the plate or strip A, and will rest against the upper edge of the apertures and will press upward, whereas the strings press downward on the ordinary sounding-board bridge.

The strip A may be made in one continual piece extending across the entire sounding-board, or may be made in sections in order to suit the particular scale.

The strip A may be fastened in any suitable manner, but I prefer to provide it with clips or lugs J J at the ends, (also in the middle,) which clips are passed through slots in the sounding-board and are bent over on the under side of the same, as shown in Fig. 2. This strip A is applicable to any stringed musical instrument. The sounding-board cannot sag between the bridge, and there is a continual tension on the strip which vibrates with the sounding-board and multiplies the vibrations, thus augmenting the quantity and quality of the tones, giving them richness and fullness.

Having thus described my invention, I claim as new and desire to secure by Letters Patent—

The combination, with a sounding-board, C, of the strings M, the bridge D, the hitch-pin block, and the apertured strip A, provided with clips, all arranged substantially as and for the purpose specified.

JOHN GOTTLIEB SEEBOLD.
